ATTORNEY

UNITED STATES PATENT OFFICE.

EDWIN AARON DONAT, OF LYNNPORT, PENNSYLVANIA.

SASH-LOCK.

1,301,407.

Specification of Letters Patent. Patented Apr. 22, 1919.

Application filed July 18, 1917. Serial No. 181,382.

To all whom it may concern:

Be it known that I, EDWIN A. DONAT, citizen of the United States, residing at Lynnport, in the county of Lehigh and State of Pennsylvania, have invented certain new and useful Improvements in Sash-Locks, of which the following is a specification.

An object of my invention is to provide a sash lock comprising essentially a spring operated latch which is loosely pivoted on a base and fastened on top of the lower window sash, the purpose in loosely pivoting the latch being to permit vertical rocking of the latch on its pivot so that the latch may be disengaged from a lug on the base and permit a spring to move the latch into a locking position immediately upon the lower window sash reaching a closed position.

Other objects and advantages will appear from the following specification, reference being had to the accompanying drawing in which:

Figure 1 is a plan view showing the device in a locked position.

Fig. 2 is a plan view showing the device unlocked, a portion of the spring casing being broken away.

Fig. 3 is a cross section through a portion of the window sashes illustrating the application of the sash lock.

Fig. 4 is an enlarged cross section taken substantially on the line 4—4 of Fig. 2.

In carrying out my invention I provide a base 1 which is secured on top of the upper rail 2 of the lower sash. A lock plate 3 is secured on top of the lower rail 4 of the upper sash. Figs. 1 and 2 of the drawing show countersunk screw holes 5.

A latch 6 is adapted to be swung beneath a keeper 7 on the locking plate 3. The keeper 7 is an integral part of the lock plate and is bent about as shown in the first three figures of the drawing. The latch 6 has a finger piece 8 which is curved in such a manner that it may be readily pulled outwardly against the tension of a spring.

The latch 6 includes a short shank 9 by which the latch is connected to a spring case 10. It will be observed in the drawing, that the spring case 10 is closed on top and open at the bottom and that it does not quite touch the upper surface of the base 1. A

rivet 11 is firmly fixed on the dog plate 1 55 and the spring case 10 is mounted thereon.

The head 12 of the rivet 11 is located a short distance above the surface of a concavity 13 which is formed in the top of the spring case 10, as shown in Fig. 3. 60

The purpose of this space is to permit a small amount of rocking movement of the latch 6 and the spring case 10 on its pivot. This slight rocking movement is in a vertical direction and is necessary to obtain the 65 release of the latch from a retaining lug when the locking dog is in the position shown in Fig. 2.

The latch 6 is retained in the unlocked position shown in Fig. 2, by the lug 14 70 which is struck up from the base 1 as clearly shown in Fig. 4. The lug 14 is adapted to enter a slot 15 formed by striking up an abutment lug 16 on the latch 6. The latch 6 is pulled over or outwardly by pulling on 75 the finger piece 8, when the lug 14 will spring into the slot 15 and engage the abutment lug 16. The latch 6 is thus held in the unlocked position shown in Fig. 2 against the tension of a leaf spring 17 in the spring 80 case 10. The spring 17 is secured at one end of the spring case 10 as shown in Fig. 2, and to the base 1 in any suitable manner as indicated at 18. It may readily be understood that the short space between the head 85 12 of the rivet 11 and the surface of the concavity 13, will permit a certain amount of play of the latch 6 and the spring case 10 so that the latch may readily pass over the lug 14. 90

A spring plate 19 is fastened to the end of the locking dog 6 opposite to the finger piece 8. The spring plate 19 may of course be stamped out of the metal of the latch or it may be formed in a manner other than that shown in the drawing. The plate 19 forms a fulcrum for the latch 6 when the latch 6 is acted on to lock the sashes together. This locking action may be either automatic or manual and is preferably automatic. It will readily be understood that when the lower sash is pulled down to close the window, the plate 19 will strike the lock plate 3 and thereby tilt the whole latch 6 with its spring case 10 until the lug 14 is 95 disengaged. The spring 17 will then drive the latch 6 over beneath the keeper 7 and into engagement with the stop 20 thus auto- 100 105

matically locking the window sashes. Of course there may be times when the latch 6 may have to be released manually. At such a time, the finger piece 8 is pushed upwardly 5 the spring plate 19 then acting as a pivot, whereupon the lug 14 is released or disengaged in the same manner above described. The spring plate 19 is formed of a strip of material which is bent to form a substantially semi-circular portion having oppositely extending ends, one end being fixed upon the latch and the other end being free, thus allowing the spring plate to expand or contract. Therefore, when the latch engages 15 the keeper, the spring plate will firmly hold the latch in engagement with the keeper.

The stop 20 is struck up from the lock plate 3 for the shank 9 of the locking dog 6 to strike against as above stated.

20 The operation of the sash lock is as follows. When the window sashes 2 and 4 to which the sash lock is applied are unlocked, the latch is pulled to the position shown in Fig. 2. When the latch assumes the position indicated, the abutment lug 16 on the latch 6 engages the lug 14 on the base 1. The lug 14 and lug 16 are held tightly in engagement by the tension of the spring 17 with the spring case 10.

25 While the construction and arrangement of the device as illustrated in the drawings is that of a generally preferred form, obviously modifications and changes therein may be made without departing from the

spirit of the invention or the scope of the 35 invention as claimed.

I claim:

In a device of the class described, the combination of a base having a vertically extending headed rivet, a spring case rotatably mounted upon said rivet and having a cavity for receiving said head, a latch carried upon the spring case, means for turning the spring case in one direction, releasable latching means engaging the latch for holding the latch in a set position, a keeper carried adjacent said base, and a spring plate formed of a strip comprising a semi-circular body having outwardly extending ends, one of said ends being fixed upon said latch while the remaining end engages the latch, whereby the spring plate is capable of expansion and contraction, said spring plate bearing upon said keeper for tilting said latch, thus causing the latching means to 55 release the latch whereupon the latch will be moved by the spring into engagement with said keeper, while said spring plate will move to hold the latch in engagement with the keeper and prevent the latch from 60 rattling.

In testimony whereof I affix my signature in presence of two witnesses.

EDWIN AARON DONAT.
